UNITED STATES PATENT OFFICE

EUGEN GEGAUF, OF STECKBORN, SWITZERLAND

MACHINE FOR SEWING OPENWORK SEAMS

Application filed April 27, 1925, Serial No. 26,002, and in Germany October 18, 1924.

This invention relates to a machine for sewing openwork seams. In these machines the two needles, arranged respectively on the right and left of the piercer, are guided in grooves provided in the latter.

In the operation of such machines three stitches are necessary for each openwork opening, the piercer and the needles penetrating the fabric. At the first stitch the needles lie in the grooves of the piercer. At the second stitch they move slightly away from the piercer, and at the third stitch the needles again lie in the grooves. Each time that the needles pierce the fabric, the thread forms a loop on the needle, which loop is grasped by the corresponding loop-taker and twisted with the thread located in the loop spool. By this twisting of the needle and loop thread, the opening made in the fabric by the piercer is hemmed. After the third stitch the fabric is shifted about 1 mm., and afterwards the previously mentioned three stitches are repeated whereby to form a ladder-like openwork. The loop-takers may be either fixed in position or hinged.

The present invention relates to a machine of this type comprising two loop-takers fixed in position and arranged one behind the other in the line of feed.

According to the invention, the needle plate and the feed dog of the feeding device are arranged relatively to the two loop-takers, so that the needle plate extends only as far as the circumference of the spool carriers placed within the loop-takers, while the feed dog also, at least in its initial position, does not overlap these carriers.

The needle plate and the feed dog are so constructed that the portion of the needle plate between the two long friction surfaces of the feed dog is connected with the portions of the needle plate lying beyond these two surfaces by members which pass under the said friction surfaces and partly enter the feed dog.

By means of this arrangement of the needle plate and feed dog with respect to loop-takers, arranged one behind the other in the line of feed it is possible to employ a reciprocating feeder in a machine for sewing openwork

seams having fixed loop-takers arranged one behind the other in the line of feed.

Hitherto the needle plates of machines for sewing openwork seams with reciprocating feeders have been constructed so that the part of the needle plate located between the two long friction surfaces is connected with the part of the needle plate lying beyond these surfaces by means of members disposed both in front and rear of the two long friction surfaces of the feed dog.

Since in machines with fixed loop-takers arranged one behind the other in the line of feed both the length of the needle plate and the length of the feed dog are limited by the relative distance apart of the spool carriers, the two long friction surfaces of the feeding device could not be extended sufficiently far for efficient feeding of the material because of the provisions of the parts connecting the needle plate in use up to the present time.

When it was desired to use reciprocating feeding devices with openwork machines and loop-takers arranged one behind the other in the line of feed, it was necessary to hinge the loop-takers with the result that not only the mechanism operating the latter, but also the spool carrier arresting mechanism were extremely complicated. As also in machines with hinged loop-takers, the needle plate, the feed dog and the presser partly covered these spool carriers the adjustment of the loop-takers could not be effected without difficulty.

According to the present invention, in which neither the needle plate, nor the friction surfaces of the feed dogs, nor the presser overlap the spool casings, after withdrawal of two slides both loop-takers are laid open so that the thread can be easily watched from the moment when it is gripped by the loop-takers until it is released, and the loop-takers can be readily and accurately adjusted. The use of a feed dog and needle plate which do not overlap the spool carriers has been known in multiple seaming machines, but the arrangement of these machines is quite different from that of machines for sewing openwork seams, and the difficulties overcome by the present invention do not occur therein.

An example of a construction according to 100

the present invention is illustrated in the accompanying drawings, in which,

Figure 1 is a plan view of the lower part of a machine with fixed rotary loop-takers arranged in series, a reciprocating feeder with fixed friction members arranged between the loop-takers, and with the needle plate;

Fig. 2 is a front elevation of Fig. 1, the loop-takers being omitted for the sake of clearness; and

Figs. 3 and 4 are separate views of the feeder and of the needle plate respectively.

As shown in the drawing, the letter *a* (Fig. 1) indicates each of two fixed loop-takers arranged one behind the other in the line of feed and in which are housed the spool casings *b* containing the spools of under thread. The friction member *d* which lies between the spool-casings *b* is secured by screws *e* in the

vertical supporting arms *c'* of the feeder *c*, the arms being connected together by an intermediate member *c²*. The needle plate *g* is secured in the machine plate *f* by screws *h*.

The needle plate is shaped so that its central part *g²*, situated between the rubbing surfaces *i'*, *i²*, is not, as heretofore, connected to the outer parts *g'* and *g³* by members situated in front and rear of the rubbing surfaces *i'*, *i²* and *i³*, but by means of a connecting member *n* which passes from the central part *g²* underneath a part of the long surfaces *i'* and *i³* and at the points *n'* enters slots *k* provided in the feed dog, and is connected above a part *d'* of the feed dog to parts *g'* and *g³* with which the needle plate is secured to the machine plate *f*. The parts *g'*, *g³* of the needle plate *g* directly abut against the rubbing surfaces at the same level and width as the central part *g²*. The letters *o* (Fig. 4) indicate slots in the needle plate into which the rubbing surfaces *i'*, *i²* and *i³* fit. The loop-takers can be covered over from above during the work by slidable plates *m*. The spool casing *b*, with the spools contained therein, can be easily taken out without the use of tools by drawing out the plates *m*. A recess *l* in the needle plate holds the tips of each of the carriers of the spool casings.

It will thus be seen that due to the elimination of the connecting members formerly provided in the front and rear of the three friction surfaces *i'*, *i²* and *i³*, the friction surfaces of the feeder can be extended in the feeding direction and that a perfectly satisfactory feed can be obtained in openwork sewing machines even when operated in high speed.

What I claim is:

1. A hemstitching-sewing machine comprising loop-takers having stationary axes arranged one behind the other in the line of feed, a spool casing in each of these loop-takers, a feeder arranged between said loop-takers, a needle-plate secured to the machine-frame, apertures in this needle plate, parts of

the feeder extending through these apertures, the dimensions on the line of feed of the needle-plate and of said parts of the feeder being less than the smallest distance between the circumferences of said spool-casings.

2. A hemstitching-sewing machine comprising loop-takers having stationary axes arranged one behind the other in the line of feed, a spool casing in each of these loop-takers, a needle-plate secured to the machine frame without overlapping said spool-casings, apertures in the needle plate at the right and left hand side of its central portion extending from the front to the rear edge of the needle plate, a feeder adapted to operate between the loop-takers, rubbing surfaces on this feeder placed in said apertures of the needle-plate and having in the initial position of the feeder at least one of their front or rear edges flush with the corresponding edge of the needle-plate, a plate mounted in the machine-plate above each loop-taker and adapted to slide in the machine-plate in the direction of feed, each of these plates abutting the corresponding edge of the needle-plate.

3. In a hemstitching-sewing machine, a needle-plate, a U-shaped feeding member beneath this needle-plate, a feed-dog secured on top of the upwardly extending arms of the feeding member, apertures in the needle-plate at the right and left hand side and in rear of the central portion thereof, rubbing surfaces on the feed-dog extending through said apertures, that portion of the needle plate between said rubbing surfaces being connected with the portions of the needle-plate lying beyond said surfaces by members which pass under said rubbing surfaces and partly enter the feed-dog, said rubbing surfaces being at least on one end flush with the corresponding edge of the needle plate in the initial position of the feeding member.

4. A sewing machine for openwork seams comprising a plurality of loop-takers having fixed axes arranged one behind the other in the line of feed, a feeder, a feed-dog mounted on the feeder, rubbing surfaces on the feed-dog, a needle plate having a central portion arranged between said rubbing surfaces, a portion of the needle plate on both sides of the central portion passing beneath one of the rubbing surfaces and extending externally thereof through the feed-dog and continuing transversely to the direction of feed above the feed-dog on a level with the central portion of the needle-plate.

5. A hemstitching sewing machine comprising loop-takers having stationary axes arranged one behind the other in the line of feed, a spool casing in each of these loop-takers, a needle-plate secured to the machine frame without overlapping said spool casings, a feeder adapted to operate between said loop-takers and provided with two vertical arms, a feed-dog secured on said arms, and

horizontal rubbing surfaces on said feed-dog on each side of the line of feed intersecting the top face of said needle-plate and operating in a path having substantially the same dimension in the line of feed as the needle-plate, this dimension being less than the shortest distance between the circumferences of the said spool casings.

In testimony whereof I affix my signature.
